US00D356044S

United States Patent [19]

Clements

[11] Patent Number: Des. 356,044

[45] Date of Patent: ** Mar. 7, 1995

[54] METAL DETECTOR

[75] Inventor: Philip E. Clements, Littleton, Colo.

[73] Assignee: Denver Dynamics, Inc., Littleton, Colo.

[**] Term: 14 Years

[21] Appl. No.: 19,810

[22] Filed: Mar. 10, 1994

[52] U.S. Cl. D10/46; D10/104

[58] Field of Search D10/46, 104, 106, 121, D10/47; 340/571, 572, 573, 540; 324/66, 67, 326, 327, 328, 329

[57]

CLAIM

The ornamental design for a metal detector, as shown and described.

DESCRIPTION

FIG. 1 is a top front perspective view of a metal detector showing my new design;

FIG. 2 is a top rear perspective view thereof;

FIG. 3 is a front elevational view thereof;

FIG. 4 is a rear elevational view thereof;

FIG. 5 is a left side elevational thereof;

FIG. 6 is a right side elevational view thereof;

FIG. 7 is a top plan view thereof; and,

FIG. 8 is a bottom plan view thereof.
